UNITED STATES PATENT OFFICE.

CHARLES A. CATLIN, OF PROVIDENCE, RHODE ISLAND.

DISINFECTANT.

SPECIFICATION forming part of Letters Patent No. 294,758, dated March 11, 1884.

Application filed June 18, 1883. (No model.)

To all whom it may concern:

Be it known that I, CHARLES A. CATLIN, of Providence, in the State of Rhode Island, have invented a certain new and useful means for disinfecting water-closets and other receptacles or conductors which are subjected to a frequent flow of water; and I do hereby declare that the following specification, taken in connection with the drawing making a part 10 of the same, is a full, clear, and exact description thereof.

The figure is a section of a water-closet, showing the arrangement for disinfecting.

The object of my invention is to provide a 15 simple, cheap, and effectual means for applying disinfectants to water-closets, water-traps, and other like places; and it consists in suspending or retaining a disinfecting material in a solid form within the bowl, closet, or trap, 20 in such a manner that it will yield the disinfecting agent to the water flowing over it.

It is well known that many places require the use of disinfectants which can only be kept in proper condition with great difficulty, on 25 account of the frequent flow of water within them, which not only removes the contents, but also the disinfecting agent itself. For instance, to keep the common water-closet in order, the disinfectant must be renewed after 30 each flushing, which not only requires the expenditure of much time, but results in a positive waste of the disinfecting material.

In the drawing, A is a water-closet, into 35 which water enters under pressure through the pipe B. C is the seat, to the under side of which is suspended from a ring, a, or other convenient device, by means of a cord, chain, or wire, a solidified ball of disinfecting compound, D. The ball D is suspended at a sufficient height to prevent it from coming in 40 contact with the water standing in the bowl, and from any contact with the water, except during the period of flushing. The disinfecting-ball D is composed of ingredients so

united that the action of the water passing 45 over it during the flushing period will have no effect upon it, so far as its dissolution is concerned, but will simply cause it to yield its disinfecting properties by parting with its exterior surface with such rapidity and in 50 such quantity as may be required until it is gradually and finally exhausted.

The ball in its composition is made the subject of separate application for patent filed in United States Patent Office July 30, 1883, Serial No. 102,310.

The operation of my invention is as follows: In discharging the contents of the water-closet or other receptacle, the valve is opened at the same time, as in the ordinary flap-pan closet, 60 permitting the introduction of the water, which, coming in through the pipe B under pressure, passes around and over the inner surface of the bowl and over the disinfecting-ball D, and fills and takes the place of the wa- 65 ter discharged.

The ball D, instead of being carried away or quickly dissolved by the frequent flushing, is gradually worn away and caused to distribute its disinfecting properties, as required, until 70 exhausted, when it is replaced by another.

The ball D is intended to be sold in the market with the chain, wire, or cord attached thereto, such suspending device being thrown away with the remnant of the ball when exhausted.

What I claim as my invention, and desire to secure by Letters Patent, is—

As a new article of manufacture, the herein-described disinfecter, consisting of the solid 80 deodorizing-ball D, provided with a length of cord or other suspending means secured to said ball, and adapted to be attached to the lid of a water-closet, substantially as set forth.

CHAS. A. CATLIN.
